UNITED STATES PATENT OFFICE.

PARKER B. HASKELL, OF LYNN, MASSACHUSETTS, ASSIGNOR OF ONE-THIRD TO WALTER B. POHLE, OF LYNN, MASSACHUSETTS, AND ONE-THIRD TO SUSAN V. RUSSELL, OF CHELSEA, MASSACHUSETTS.

SPLASH TROUGH FOR CRANK CASINGS.

Application filed February 6, 1925. Serial No. 7,332.

This invention relates to splash troughs for internal combustion engines and has for its object the provision of means whereby the sediment in the oil may be collected and withdrawn from all of the troughs simultaneously without disturbing the troughs or securing access to the interior of the casing.

These objects are obtained by the mechanism illustrated in the accompanying drawings.

For the purpose of illustrating the invention one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents a vertical transverse section of a crank casing provided with a plurality of splash troughs and a sediment removing device embodying the principles of the present invention.

Figure 2 represents a vertical section of the same on line 2, 2 on Fig. 1, and

Figure 3 represents an elevation of one end of the casing and showing the means for inverting the sediment collector.

Similar characters indicate like parts throughout the several figures of the drawings.

In the drawings, 10 is a crank casing provided with a plurality of splash troughs 11, each having an oil-containing compartment 12 contained therein.

The usual crank 13 is mounted upon a revoluble shaft 14 pivotally connected at its outer ends to a connecting rod 15.

As the shaft 14 revolves the pivotal connection between the outer end of the crank 13 and the connecting rod 15 splashes through the oil contained in the compartment 12 and is thoroughly lubricated.

In the drawings the splash troughs are shown as formed integral with the casing 10 which is provided with a bottom 16.

Each oil trough 11 has a downwardly projecting lug 17 in which is formed a cylindrical chamber 18, the chambers 18

of the various splash troughs 11 being in alignment.

The chamber 18 in each of the oil troughs 11 communicates by a passage 19 with its oil-containing compartment 12.

In the end walls of the casing 10 and in alignment with the chambers 18 are formed bearings adapted to receive a tubular member 20, this tubular member extending through stuffing boxes 21 at the opposite ends of the crank casing 10.

The tubular member has formed therein openings 22 which are adapted to register with the passages 19 in the splash troughs 11.

The member 20 is shown in the drawings 70 in its normal position, and under these conditions any sediment in the oil contained in the compartment 12 will settle into the tubular member 20.

Collars 23 are secured to the member 20 75 to provide a means for preventing end movement of the tubular member.

To one end of the tubular member 20 is secured an arm 24, which when the tubular member 20 is in its normal position is locked 80 to the casing 10 by means of the bolt 25 as shown in Fig. 3.

Stop members 26 and 26^x extend outwardly from the wall of the crank casing to limit the movement of the arm 24 in either direction.

The opposite ends of the tubular member are provided with closures 27 and packing members 28.

When it is desired to clear the tubular member 20 from any sediment which may have collected therein, the arm 24 is moved counter-clockwise against the stop member 26^x.

When this is accomplished the openings 95 22 in the member 20 are moved out of register with the passages 19, thereby preventing any further oil from entering the tubular member 20.

The arm then may be locked in its lowest 100 position by inserting the bolt 25 into the threaded lug 29.

The closures 27 are then removed from the opposite ends of the tubular member and any suitable cleaning tool may be inserted 105 into the bore of this member and all of the sediment removed therefrom.

If desired only one of the closures 27

may be removed and a pump attached to the open end of the tubular member 20 and the sediment may then be drawn from the bore thereof.

5 As soon as the tubular member 20 has been cleared of its sediment, the closures 27 are again positioned on the ends of said member and the arm 24 moved into contact with the stop member 26, and secured in this 10 position by the bolt 25.

This makes a very simple device for removing the sediment from splash troughs and one which may be operated very quickly so that the engine may be maintained in 15 commission at all times.

It does away with the necessity of dismantling the crank casing in order to gain access to the oil troughs when it is desired to remove the sediment therefrom.

20 This is a great advantage particularly when the engine is mounted upon a fire truck which is liable to be called for duty at any moment.

25 It is believed that the operation and many advantages of the invention will be understood without further description.

Having thus described my invention, I claim—

1. In a crank casing for internal combustion engines, a splash trough extending transversely thereof having an oil-containing compartment with a discharge opening in the lowest part of the bottom thereof; a pipe extending through a wall of said casing and having a hole in the periphery thereof normally registering with said dis-

charge opening; means for oscillating said pipe; and removable closures for the opposite ends of said pipe.

2. In a crank casing for internal combustion engines, a plurality of splash troughs therein, each having an oil-containing compartment with a discharge opening in the lowest part of the bottom thereof; a pipe extending through a wall of said casing and all of said troughs and having in the periphery thereof holes normally registering with said discharge openings; means for oscillating said pipe; means preventing end movement of said pipe; removable closures for the opposite ends of said pipe; an arm secured to the outer end of said pipe for imparting a partial rotation thereto; and means for locking said arm to said casing.

3. In a crank casing for internal combustion engines, a splash trough extending transversely thereof having an oil-containing compartment with a discharge opening in the lowest part of the bottom thereof; a tubular sediment chamber extending through the opposite walls of said casing and having a hole in the periphery thereof normally registering with the discharge opening; means for moving said chamber so that said hole will be out of register with the discharge opening; and removable closures for the opposite ends of said chamber.

Signed by me at 746 Old South Bldg., Boston, Mass., this 3rd day of February, 1925.

PARKER B. HASKELL.
